UNITED STATES PATENT OFFICE.

NELSON GOODYEAR, OF NEW YORK, N. Y., ASSIGNOR TO J. B. COLT COMPANY, OF NEW YORK, N. Y., A CORPORATION OF NEW JERSEY.

ACETYLENE-GENERATOR.

SPECIFICATION forming part of Letters Patent No. 783,193, dated February 21, 1905.

Application filed January 21, 1904. Serial No. 189,950.

To all whom it may concern:

Be it known that I, NELSON GOODYEAR, a citizen of the United States, and a resident of the borough of Manhattan, city, county, and State of New York, have invented certain new and useful Improvements in Acetylene-Generators, of which the following is a specification accompanied by drawings.

The objects of the invention are to improve acetylene and similar generators and overcome the defects and disadvantages of many of the forms now in existence.

The precise nature of the several features that constitute the invention will be best understood from the following description and enumerated in the claims.

It is highly desirable and, in fact, necessary that means be provided whereby air is admitted to the generating-chamber when water is being withdrawn therefrom and that the air from substantially the entire gas-space be permitted to escape when water is being admitted thereto. According to this invention the generator is vented to the atmospheric air both upon charging water into the machine and upon flushing out.

Further objects of the invention will hereinafter appear; and to these ends the invention consists of apparatus for carrying out the above objects embodying the features of construction, combinations of elements, and arrangement of parts having the general mode of operation substantially as hereinafter fully described and claimed in this specification, and shown in the accompanying drawings, in which—

Figure 1 is a sectional view of a generator embodying the invention. Fig. 2 is an elevation of a modified form of generator for carrying out the invention. Fig. 3 is a plan view of Fig. 2, partly in section. Fig. 4 is a vertical sectional view of Fig. 2. Fig. 5 is a detail view of one of the interlocking connections shown in Fig. 4.

In Fig. 1 a suitable form of generator is illustrated, to which the invention is applied. This application in so far as Fig. 1 is concerned and the description thereof being in part a division of my copending application, Serial

No. 65,811, filed June 24, 1901, I have shown 50 by way of preference a portion of the same drawing as that illustrated in my copending case. Referring to Fig. 1, the generator preferably combines an outer casing 25, within which is fitted a water-sealed bell 26, that carries the carbid-hopper 22. The water from the generating-chamber may be flushed out through any suitable flush-out mechanism—such, for instance, as the cock 30 shown. The cock carries a sector or stop 31, which in a 60 closed position of the cock interferes with the descent of a rod 32, having connections 33 and 34 with the instrumentality 35, that serves to secure the carbid-feeding cover 36 when closed. This feature of the apparatus is 65 claimed in the parent case, Serial No. 65,811. The connections described have a relation to the invention in that it prevents the opening of the cover 36 until the flush-out cock 30 is open, thereby insuring the depletion of the water 70 seal 75. The seal 75 might not be depleted on drawing the water from the generator if the cover 36 had been opened first, since the valves 50 and 60 do not always make a tight joint with their seat. From the stirrup 38 a rod 67 75 and connection 66 extend, connected to operate a downwardly-extending rod 65. (Shown broken away.) This device is adapted to form an interlock with the carbid-feeding mechanism, as fully set forth in my prior application, 80 Serial No. 65,811, the interlocking connections being omitted in this case, as they form no part of the present invention. The carbid-hopper has preferably a converging bottom, as shown. A duplex carbid-feeding valve is 85 provided, the inner member 50 of which is operated by a lever 51, fulcrumed in the hopper. Surrounding the valve 50 is an annular valve or stop 60, which has a lost-motion connection with the valve 50, so that the rise of said valve 90 50 beyond a small limit will raise the valve 60 and allow the carbid to feed, and, conversely, in closing the valve 60 will first seat itself and then the valve 50 will descend and seat itself. The valves and the lever 51 are inclosed within 95 a casing, which is preferably roof-shaped, above the lever 51, as shown in the figures, and which extend down around the valves in

a way to prevent the entire mass of carbid pressing down upon the valves and interfering with their operation. There is provided a safety valve or stop 70, mounted to swing 5 under and cut off the feeding of carbid from the hopper when free to move, but normally held in coöperative position, as shown in Fig. 1, by a detent 31, connected as shown, to be supported by a float 73. If for any reason 10 the water-level within the generator is forced either by an excess of gas-pressure or the drawing off of the water, the fall of the float 73 draws down the detent 71 and releases the safety valve or stop 70, causing it to swing beneath the valve-opening and prevent any feeding of carbid. The gas passes from the generating-chamber to the gasometer through 15 gas-pipe 83. In order to reduce the fluctuations of pressure which occur by the sudden 20 feeding of carbid within the generator, an annular space 80 of large area is provided above the generating-chamber, into which the water may be freely forced by an excess of pressure, as indicated by the arrow 81. The space 80 therefore forms a partial reservoir into which a considerable volume of water may be forced by an excess of pressure within the generator. The water flows back into the generating-chamber as the excess of pressure is relieved 25 30 by the escape of gas into the gasometer. In order to insure the venting of the machine both when introducing and withdrawing water, suitable means are provided in accordance with the invention. This means, presently to be described, prevents the formation of a partial vacuum in the generator when drawing off water and also prevents air being forced into the gasometer when the generator is being filled with water. In Fig. 1 a special automatic trap is employed for carrying out the 35 invention. As shown, a water-holding vessel 75 is supported somewhat above the normal water-level in the generator and substantially at the top of the generating-chamber, 40 and into this dips and is sealed a vent-pipe 76, which communicates above with the atmosphere. Surrounding the lower end of the vent-pipe 76 is a depending sleeve 77, which is also water-sealed in the receptacle 75, and 45 50 it is closed gas-tight at its upper end. Assuming that the sleeve 77 extends, say, three inches down into the water within the vessel 75, air will be admitted freely to the interior of the generator as long as the pressure within 55 it is reduced to three inches less than atmospheric pressure. As, however, the horizontal section of water admitted within the sleeve 77 is large as compared to the annular space intervening between the sleeve and the walls 60 of the vessel 75, the admission of air in carrying down the water-level within the sleeve 77 depletes the amount of water within the receptacle 75, so that the air may escape still more freely from the generating-chamber 65 when the water is being introduced to refill

the generator. As soon, however, as the water in the generator rises high enough to pour into and fill the vessel 75 it of course reestablishes the seal, because then the water will reach the foot of the air-pipe 76 and completely seal it against the escape of air or gas. Therefore it will be seen that this special trap admits air readily to the generator and also permits the escape of air while the generator is being filled with water; but as soon as the generator is filled it reestablishes the complete sealing of gas within the generator. 70 75

In Figs. 2, 3, 4, and 5 a different mode of carrying out the invention is illustrated as a modification which has been found to operate efficiently and well. While the generator may be constructed in any suitable manner, I have preferably shown the same form of construction illustrated in my copending application, Serial No. 142,613, filed February 9, 1903. In this form of generator there is a partition E inside of the outer casing D, the walls of which are extended upwardly at F to form what may be termed a "filling-bib," 80 85 90 communicating with the inside of the generator by means of a downwardly-extending sleeve G, which forms a water seal for the stirrer-rod H, suitably connected to the stirrer I. The filling-bib is partly covered over by the top J, while a suitable hinged lid or cover K affords provision for charging the machine with water. As shown in the drawings, the neck L of the machine is supported from the partition E and extends upwardly 95 100 through the top J, supporting the hopper O, within which is arranged the carbid-valve. Any suitable mechanism may be provided for operating the valve, none, however, being shown in this instance, as it forms no part of the present invention. An overflow-opening j is provided in a suitable position on the generator and suitable pipe connections k are provided leading from the generator, while a vent-pipe l communicates with the outside atmosphere. The vent-pipe l also communicates with the inside of the generator, as shown in this instance through the interposition of the piping k, while a vent-cock q is arranged in the vent-pipe l to control the 110 115 120 125 130 same. The lid or cover K, as shown, is provided with a hinged pivot-rod r at one side, (best shown in Fig. 4,) while at the other side said cover is connected to the vent cock or valve q, whereby in opening and closing the cover K the valve q will be operated. Any suitable means may be provided for operatively connecting the lid or cover K to the valve q, as shown, the lid K being provided with a socket s, into which fits a squared projection t on the valve. The arrangement of the filling cover or lid K, operatively connected with the vent q, insures the venting of the machine when introducing water into the same, because when the lid is opened the vent- 130

cock is opened. In order to insure the venting of the machine when water is being withdrawn, in this instance, as shown in the drawings, interlocking connections are provided, 5 including the cover K and operatively connecting the vent and the flush-out. The flush-out or lime-gate u, as shown, is provided with an upwardly-extending rod v, the upper end of which extends within the socket w for the 10 hinged pivot r of the lid K. The pivot r is provided with a flattened or recessed portion x, which moves into such position when the lid K is opened that the rod v may move upwardly past said flattened portion of the pivot 15 r; but when the lid K is closed the rod v cannot be moved upward. According to this construction the lime-gate u cannot be opened unless the lid K is opened, and it will also be seen that the lid K is locked open as long as 20 the lime-gate u remains open, because when the interference-rod v is moved upward past the flattened portion of the pivot r the lid cannot be closed again until the rod v is lowered. The object of locking the water-charging 25 rod or cover K open in the construction described when the lime-gate is open is to prevent the drawing off of the residuum of water with the closed vent, for it will be seen that by locking the lid K open the vent q is 30 also locked open. Other suitable interlocking connections may be provided, if desired, between the lime-gate and the vent q without departing from the spirit of the invention.

It will thus be seen that widely-differing 35 forms of apparatus may be provided for carrying out the leading objects of this invention--namely, to insure the venting of the machine both when charging water in and flushing out. In Fig. 1 a special automatic 40 trap is shown, while in the remaining figures positive mechanical interlocking connections are provided between a vent-cock and a flush-out. The invention, broadly considered, therefore contemplates any suitable operative 45 means for carrying out the objects of the invention, as hereinbefore stated.

The mechanical interlocking devices herein shown and described in connection with Figs. 2, 3, 4, and 5 form the specific subject-matter 50 of some of the claims of my copending application, Serial No. 142,613, filed February 9, 1903, the generic claims in this present application being applicable to both forms of apparatus shown herein, with specific claims 55 for the subject-matter of Fig. 1.

Obviously the invention may therefore be embodied in widely-varying forms without departing from the spirit of the invention. For this reason, without enumerating any 60 further equivalents, I claim, and desire to obtain by Letters Patent, the following:

1. In a generator, the combination of means 65 for venting the generator to atmospheric air, a flushing-out device, and means for charging the generator with water, with operative

means so constructed and devised, that the venting of substantially the entire gas-space of the machine is insured both on charging in water and upon flushing out, for substantially the purposes set forth. 70

2. In a generator, the combination of a vent to atmospheric air situated at the top of the generating-chamber, and a flush-out, and means for venting the machine to atmospheric air both on charging in or withdrawing water 75 from the machine, for substantially the purposes set forth.

3. A generator, having means for flushing out and for venting the same to atmospheric air, said vent being situated at the top of the 80 generating-chamber, with controlling means for the vent acting to connect the machine with atmospheric air when said machine is at least partially empty and water is charged in, and also when the machine is full and water 85 is withdrawn therefrom for substantially the purposes set forth.

4. In a generator, the combination of means for venting the generator to atmospheric air situated at the top of the generating-chamber, 90 a flushing-out device, and means for charging the generator with water, with operative means so constructed and devised that provision for the venting of the machine is insured both on charging in water and upon 95 flushing out, during the operation of charging in or flushing out, for substantially the purposes set forth.

5. In a generator, the combination of a vent to atmospheric air, and a flush-out, and automatic means for venting substantially the entire gas-space of the machine to atmospheric air both on charging in or withdrawing water 100 from the machine, for substantially the purposes set forth. 105

6. A generator, provided with means for flushing out and for venting the same to atmospheric air, with controlling means for the vent acting to automatically connect substantially the entire gas-space of the machine with atmospheric air when said machine is at least partially empty and water is charged in, and also when the machine is full and water is withdrawn therefrom, for substantially the purposes set forth. 110

7. In a generator, the combination of means for venting substantially the entire height of the generator to atmospheric air, a flushing-out device, and means for charging the generator with water, with operative means so constructed and devised that the machine cannot be charged with water or flushed out without the provision of an open vent to atmospheric air, for substantially the purposes set forth. 115

8. In a generator for acetylene and the like, 120 the combination of flushing-out device, water-charging device and a venting device for venting substantially the entire gas-space of the generator to atmosphere during the charging in of water, and letting in air during the flush- 125 out. 130

ing out, provided with a means for freely opening the said vent during the said charging in and flushing out.

9. In a generator for acetylene and the like, 5 the combination of a flush-out and a means for freely venting substantially the entire height of the apparatus to atmospheric air when charging in water or withdrawing water from the machine.
10. In a generator of the type in which a 10 large body of water is employed and in combination with the water-holding receptacle thereof, means for flushing out the apparatus, means for charging in the water, and a vent situated 15 at the top of the water-holding receptacle and provided with means for freely admitting air when the water is flushed off and permitting air to escape when the water is charged in.
11. In a generator of the type in which a 20 large body of water is employed and in combination with the water-holding receptacle thereof, means for flushing out the apparatus, means for charging in the water, and automatic means coöperating with the said devices for letting in air when the water is flushed out and for permitting the air from substantially the entire 25 gas-space to escape during the charging in of the water.
12. In a generator of the type in which a 30 large body of water is employed and in combination with the water-holding receptacle thereof, means for flushing out the apparatus, means for charging in the water, and automatic means for admitting air during the flushing-out operation and permitting the air from substantially 35 the entire gas-space to escape during the charging-in operation, provided with means for water-sealing the last-said means when the water reaches a predetermined height.
13. In a generator of the type in which a 40 large body of water is employed and in combination with the water-holding receptacle thereof, means for flushing out the apparatus, means for charging in the water, and automatic means 45 situated at the top of the water-holding receptacle for the admission and exit of air during the flushing out and charging in of the water,

said means including a water-sealing device therefor from which water is at least partially exhausted upon the reduction of pressure within the generator beyond a predetermined limit, said means being located at a height to be replenished when the water is charged in to a predetermined height.

14. In combination in a generator for acetylene and the like, 55 a carbid-chamber and a water-holding chamber adapted to hold a considerable body of water, means for charging in the water and means for flushing it out, means for charging in the carbid and a connection or vent situated at the top of the water-holding chamber independent of the carbid-charging opening, flushing-out opening and water-supply inlet for maintaining substantially atmospheric pressure during the flushing 60 out and charging in of the water.

15. A generator having means for flushing out and for venting the same to atmospheric air, said vent being situated at the top of the generating-chamber, with controlling means 70 for the vent acting to connect the machine with atmospheric air when said machine is at least partially empty and water is charged in.

16. In a generator, the combination of a 75 vent to atmospheric air situated at the top of the generating-chamber, and a flush-out, and means for venting the machine to atmospheric air on charging in water substantially for the purposes set forth.

17. In a generator, the combination of means 80 for venting the generator to atmospheric air, a flushing-out device, and means for charging the generator with water, with operative means so constructed and devised that the venting of substantially the entire gas-space of the machine is insured upon charging in water.

In testimony whereof I have signed this specification in the presence of two subscribing witnesses.

NELSON GOODYEAR.
